CONTROL BOARD

Frank F. Pfeiffer, Dayton, Ohio, assignor to The
Reynolds & Reynolds Company, Dayton, Ohio,
a corporation of Ohio

Application December 3, 1945, Serial No. 632,529

4 Claims. (Cl. 40—19.5)

1

This invention relates to a method and apparatus for following up various items of business transactions, and in particular for following up on repairs to cars of automobile owners.

It is the object of this invention to provide a follow-up system and mechanism so that an automobile service station owner or dealer may continuously check the service rendered to his customers on their automobiles.

It is an object of this invention to provide visual data for indicating the status of service on a variety of automobiles owned by different customers.

It is a further object to provide means of visually indicating by position and color the classification, date of service and other details to enable the service station or garage owner to continuously follow up on his customers' service requirements to insure that their automobiles are promptly taken care of when the service is needed by the automobiles.

In particular it is the object of this invention to provide means of indicating the months in each classification and the dates of the month in each classification by a simple means which can be adjusted daily without removing the indicating tags of the customers.

It is also an object to provide means of removing groups of tags bodily from one date classification to another date classification.

Referring to the drawings:

Figure 1 is an elevation of a typical board.

Figure 2 is a detailed view of the date slide mechanism.

Figure 3 is a view showing in detail the ticket or tag that is hung on the board.

Figure 4 is a diagrammatic view showing the method of operation of the board and the four-group classification of the board.

Figure 5 is a perspective section of two of the movable panels.

Figure 6 is a vertical section through one of the panels illustrating the ease with which the panel may be removed.

Referring to the drawings in detail, I generally designate a board having a frame 2 for decorative purposes. This board is divided into four major date groups: group 3 is from 1 to 31 days; group 4 is from 31 to 60 days; group 5 is from 61 to 90 days; and group 6 is from 91 to 120 days. Each date group has basically the same structure. In the left-hand column there are a series of indicator cards 7, 8, 9, 10, 11, 12, 13 and 14 which designate certain letters of the alpha-

2

bet which indicate the first letters of the names of the customers. All tickets 15 which are hung on the hook 16 that are aligned horizontally opposite a particular group of letters have customers whose names begin with one of those letters. This facilitates locating the tickets on the board.

The hooks 16 are mounted upon the removable panels 17. The panels 17 are located horizontally opposite the indicator cards which provide an alphabetical classification panel and beneath the dates of the month from 1 to 31 which are arranged horizontally, such a listing of the dates being arranged at the top of each of the groups 3, 4, 5 and 6. Slidably mounted upon these date-carrying slide carrier means designated 18 and having the numeral tickets 19 is a date-indicator slide 20. This date indicator slide is provided with side carriers 21 for carrying the tickets 22 on which the indication of the month is placed.

20 The side carriers have between them an opening 23 which discloses the particular day of the month to which the board is adjusted. In Figure 2 the indication reads that it is the 10th of November. The November days which have expired are

25 shown on the left-hand and the October days on the right-hand. Each of the slides 20 is provided with a successive month indication on each side of the opening 23 for each panel represents a part of two successive months. That part of

30 the panel on the left-hand side of the slide 20 in group 3 indicates the current month while that on the right-hand side of the slide 20 indicates the preceding month. Therefore, since each of the groups 3, 4, 5 and 6 each represents a part of two

35 months, the most recent month being indicated on the left-hand side of the slide and the preceding month on the right-hand side of the slide 20, the month indications on the slide are a great aid in quickly reading the board.

40 As seen in the diagram in Figure 4, the date indicator slides 20 have successively different pairs of months indicated in groups 3, 4, 5 and 6.

The advantage of this board is that it eliminates the difficulties of the prior art in connection with a reversely-arranged date indicator

45 such as shown in the patent to Kimball 2,192,679 which was difficult to operate, difficult to understand, and very confusing. By arranging the dates in the correct numerical order as regularly used on calendars and by associating those dates with each group without reference to any master date indicator, great simplicity has been accomplished, which enables these boards to be operated by people of small skills. This is particularly true in having the date indicator slide 20 associ-

ated with each date group so that the date can be immediately read.

Method of operation

Assuming the board has been in operation, the various panels 3, 4, 5 and 6 will be covered with colored customer control tags 15. It is desirable to have separate colors for each row of alphabetical groups 1 to 14 inclusive. This speeds up and facilitates the handling of the tags of various customers.

The operator takes up the condition of the board on a given day in order to bring it up to date, and his actions are as follows.

Let us assume that the day is the 10th of November with the slide 20 of group 3 having the indicia Nov.—Oct.:

(1) The operator removes panel 17 of today's date from top 30-day field, group 3; and mails out a 30-day warning card to each of the customers thereon because it has been 30 days since customer received service, these tags having been placed on the board on October 10.

(2) He then removes panel 17 from second 30-day field, group 4; inserts first 30-day field panel; and mails out 60-day warning cards to the customers thereon. They have not received service for 60 days.

(3) He removes panel 17 from third 30-day field, group 5; inserts second 30-day field panel, and mails out 90-day warning cards.

(4) He removes panel from fourth 30-day field, group 6; and inserts third 30-day panel. He mails out 120-day warning cards. He then puts tags 15 on a delinquent board and places this empty panel 17 in top field.

(5) The operator now takes receipts from previous day's service, gets customer's names therefrom, makes out new tags where necessary and adds to top field panel 17 in group 3 which has been emptied by operation 4.

(6) He then moves all date indicator slides 20 over one day in readiness for November 11 operation.

(7) At end of month, he moves top date indicator to second field, second to third, third to fourth, fourth to box file, and places new indicator from his box file in top field.

A typical board is shown diagrammatically in Figure 4. The purpose is to show in enlarged form the arrangement by months.

Figure 6 illustrates the ease with which the panels 17 may be removed from their date groups for transfer to another date group. The panel 17 is raised by means of a hook 16 until said panel contacts the ledge 1a of board 1, thus making it possible to swing the lower edge of panel 17 clear of ledge 1b of the board 1.

It will be understood that it is desired to comprehend within this invention and the herein-after appended claims, such changes and modifications as may be necessary to adapt this invention to various conditions of uses.

Having thus fully described my invention, what I claim as new and desire to secure by Letters Patent, is:

1. In combination, in a display board, a plurality of horizontally disposed parallel date carrying slide carriers each having a plurality of like numerals representing days of the month, a plurality of indicia tags, a plurality of groups of removable panels removably held on the display board by said slide carriers and having supports thereon for supporting said indicia tags, vertically arranged alphabetical classification

panels opposite each row of supports on said panels for the said tags, a plurality of tickets, a slidable date indicator on each of said slide carriers comprising means for removably supporting one of said tickets on each side thereof for displaying a selected date indicated by one of the numerals, each ticket serving to conceal adjacent numerals, said date indicator having a central aperture between each of said ticket supporting means, said aperture serving as a viewing window whereby to observe one of said numerals representing a day of the month, and whereby to observe from one side of said indicator the number of days in the current month and to observe on the opposite side of said indicator the number of days of the preceding month.

2. In combination, in a display board, a plurality of T-shaped horizontally disposed parallel date carrying slide carriers each having a plurality of like numerals representing days of the month, a plurality of indicia tags, a plurality of groups of removable panels removably held on the display board by said slide carriers and having supports thereon for supporting said indicia tags, vertically arranged alphabetical classification panels opposite each row of supports on said panels for the said tags, a plurality of tickets, a slidable date indicator on each of said slide carriers comprising means for removably supporting one of said tickets on each side thereof for displaying a selected date indicated by one of the numerals, each ticket serving to conceal adjacent numerals, said date indicator having a central aperture between each of said ticket supporting means, said aperture serving as a viewing window whereby to observe one of said numerals representing a day of the month, and whereby to observe from one side of said indicator the number of days in the current month and to observe on the opposite side of said indicator the number of days of the preceding month.

3. In combination, in a display board, a plurality of horizontally disposed parallel date carrying slide carriers each having a plurality of like numerals representing days of the month, a plurality of indicia tags, a plurality of groups of removable three-sided panels removably held on the display board by said slide carriers and having supports thereon for supporting said indicia tags, vertically arranged alphabetical classification panels opposite each row of supports on said panels for the said tags, a plurality of tickets, a slidable date indicator on each of said slides comprising means for removably supporting one of said tickets on each side thereof for displaying a selected date indicated by one of the numerals, each ticket serving to conceal adjacent numerals, said date indicator having a central aperture between each of said ticket supporting means, said aperture serving as a viewing window whereby to observe one of said numerals representing a day of the month, and whereby to observe from one side of said indicator the number of days in the current month and to observe on the opposite side of said indicator the number of days of the preceding month.

4. In combination, in a display board, a plurality of horizontally disposed parallel date carrying slide carriers each having a plurality of like numerals representing days of the month, a plurality of indicia tags, a plurality of groups of removable three-sided panels removably held on the display board by said slide carriers and having supports thereon for supporting said indicia

tags, vertically arranged alphabetical classification panels opposite each row of supports on said panels for the said tags, a plurality of tickets, a slidable date indicator on each of said slides comprising means for removably supporting one of said tickets on each side thereof for displaying a selected date indicated by one of the numerals, each ticket serving to conceal adjacent numerals, said date indicator having a central aperture between each of said ticket supporting means, said aperture serving as a viewing window whereby to observe one of said numerals representing a day of the month, and whereby to observe from one side of said indicator the number of days in the current month and to observe on the opposite side of said indicator the number of days of the preceding month, said slide carriers projecting from said board and having shoulders for engaging one of the sides of said panels.
